(57) **CLAIM**

The ornamental design for a phone case, as shown and described.

DESCRIPTION

FIG. 1 is a back and right-side perspective view of a phone case showing my new design;

FIG. 2 is a front elevational view thereof;

FIG. 3 is a back elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an interior elevational view thereof showing the phone case in an open state;

FIG. 9 is a back and right-side perspective view thereof showing the phone case in a rotated and open state; and, FIG. 10 is an interior perspective view thereof showing the phone case in an open state.

The broken lines form no part of the claimed design and depict linear elements and portions of the phone case that form no part of the claimed design.

1 Claim, 10 Drawing Sheets
